Filed Jan. 11, 1973, Ser. No. 322,704

Claims priority, application Germany July 12, 1972

Term of patent 3½ years

Int. Cl. D6—04

U.S. Cl. D6—4

FIG. 2

FIG. 3

FIG. 4

FIG. 1 is a perspective view of a combined work desk, bed and multiple storage unit of our new design;

FIG. 2 is a front view of a combined work desk, bed and multiple storage unit, seen in direction of arrow 2 in FIG. 1;

FIG. 3 is a side view of a combined work desk, bed and multiple storage unit, seen in direction of arrow 3 in FIG. 1;

FIG. 4 is an opposite side view of a combined work desk, bed and multiple storage unit;

FIG. 5 is a rear view of a combined work desk, bed and multiple storage unit; and

FIG. 6 is a top view of a combined work desk, bed and multiple storage unit.

We claim:

The ornamental design for a combined work desk, bed and multiple storage unit, substantially as shown.
